REMOVAL OF LIQUIDS FROM DRUMS OR OTHER CONTAINERS
 Victor William Smirles, 14 Kings Road, Cheadle Hulme, England
 Filed May 7, 1959, Ser. No. 811,676
 3 Claims. (Cl. 137—270)

This invention relates to improvements in the removal or withdrawal of liquids from drums or other containers.

Motor fuels and other light hydrocarbons and other liquids are frequently stored in drums or containers from which they are dispersed through a tap adjacent the bottom of the drum or container and difficulty is experienced in preventing the tap from dripping when not in use.

According to the invention a discharge device comprises a tubular plug provided with a ball valve screwed into the bung of the barrel or container and a delivery tube for screwing into the plug provided with means for lifting the ball off its seat, the delivery tube during transit being reversed or secured to the filling cap for the drum or container.

The invention will be described with reference to the accompanying drawings:

FIG. 1 is longitudinal section of the device in the closed position.

FIG. 2 is a similar view showing the device in the open position.

FIG. 3 is a side elevation partly in section showing the device housed for transport.

FIG. 4 is a side elevation to a smaller scale showing the device mounted in a drum.

FIG. 5 is a detail view showing the device housed in the filler cap of a drum.

The discharge device A in the form of a tubular plug is constructed with a body portion having a flanged portion *a* and screwed at each end *a*¹, one screw engaging a screwed bung *b* in a barrel or container B when the device is in operation (FIGS. 1 and 2) and the other screw engaging the screwed bung *b* when the device is housed for transit (FIG. 3).

The body portion is formed with a shoulder to form a seating *a*² for a ball valve C. A spring *c* is inserted into the body behind the ball C to retain it on its seating, the other end of the spring *c* bearing on a pin or on a ring *c*¹ screwed into the body portion. The device is screwed into the normal bung *b* opening in the drum, container or barrel B. During transit a sealing cap *a*⁴ may be screwed onto the outer end tube to enclose the ball valve.

The body portion is recessed at the opposite end to receive a delivery tube or bib D formed with a flange *d* by which it is secured in position by a flanged nut *D*¹ screwed on to a screwed portion *a*³ on the body. The delivery tube is formed with a delivery aperture *d*¹ from a chamber *d*² and with a recess *d*³ to receive the end of a control rod D².

The control rod D² is formed with a shouldered portion *d*⁴ to engage one wall of the discharge chamber to prevent its withdrawal therefrom. The inner end of the control rod engages the ball C to lift it off its seat (FIG. 2).

As an alternative to the housing of the device during transit as shown in FIG. 3 the delivery tube D may be removed by unscrewing the nut D¹ and screwing the tube D into a disc E housed in the filling cap E¹.

2

The discharge tube or bib D may be turned with the aperture *d* facing upwards when not in use.

To discharge the contents of the barrel or container B, the sealing cap *a*⁴ is removed and the delivery tube D is screwed on to the end of the body A in place thereof. The control rod D² is depressed to lift the ball C off its seating and liquid is discharged through the aperture *d*¹ which may be adjusted to discharge vertically downwards. In order to maintain the ball C off its seat a U-shaped member B¹ may be pivoted on the drum to engage over the end of the control rod D². A gauge may be provided in the discharge aperture *d*¹.

Alternatively, the recess *d*³ in the discharge tube D may be tapered to receive a tapered end *d*⁵ on the control rod D² and the control rod when depressed will retain the ball C off its seating. To release the ball C the control rod may be turned in the discharge tube to release the end *d*⁵ and the spring *c* will then close the ball C on to its seating *a*²; or the control rod D² may be threaded to 20 screw into the recess *d*³ or into the wall.

The plug A and bib or discharge tube D may be formed of plastic material such as polyethylene or other material unaffected by the contents of the drum or container or the plug D may be of metal with a lining of polyethylene or other plastic material.

I claim:

1. A discharge device comprising a hollow plug having a body defining a valve chamber containing a spring closed valve and longitudinally spaced similar externally threaded mounting sections, a reduced threaded end section on the plug axially beyond one of said spaced similar threaded sections, releasable means for mounting a delivery tube having a lateral liquid discharge outlet on said reduced threaded end section, and a control plunger reciprocably mounted in the tube for actuating said valve.

2. The discharge device defined in claim 1 wherein said tube is flanged at its inner end to bear against the reduced threaded end section of said plug and a nut mounted on said reduced threaded end section having a flange for securing the tube to the plug in a selected position of rotation of the tube to orient the discharge outlet in a desired direction.

3. The device defined in claim 2 wherein said tube and plug have interfitting smooth conical end surface engagement radially inwardly of the tube flange abutment against the plug end.
